2 Claims

ABSTRACT OF THE DISCLOSURE

A scaffold frame including an elevated platform and running gear with two transversely spaced traveling wheels. A pair of occupant actuated, independently rotatable cranks are provided on the frame adjacent the platform and drive shafts extend downwardly from the respective cranks, the drive shafts being operatively connected to the respective traveling wheels by gearing, so that the scaffold may be propelled by its occupant. Steering is effected by independent driving of the traveling wheels.

This invention relates to new and useful improvements in scaffolds such as are commonly used by painters, construction workers, and the like, and which are usually provided with traveling wheels or casters so that they may be moved from one location to another as required by progress of the work. The worker using a scaffold of this type usually occupies a position on an elevated platform of the scaffold, and if the scaffold is to be moved, the worker must leave his platform and lower himself to the ground or floor in order to propel the scaffold from one location to another. Otherwise, a worker's assistant must be employed to move the scaffold while the worker remains on the platform.

The principal object of the invention is to eliminate the above outlined disadvantages of conventional scaffolds so that the worker may propel the scaffold himself from one location to another without leaving his position on the elevated platform, so that considerable time and effort may be saved in performance of the work and also that employment of an assistant is not necessary in order for the scaffold to be moved.

This object is attained by the provision of an occupant propelled scaffold wherein independently rotatable hand cranks are provided on the scaffold frame adjacent the platform and are operatively connected by shafts and gearing to the traveling wheels, so that by simply rotating the cranks, the occupant may propel the scaffold from one location to another without leaving his platform. Also, steering of the scaffold is effected by driving, as afforded by independent rotation of the hand cranks.

Another important feature of the invention is that the propelling means may be easily and conveniently applied to scaffolds of conventional construction without requiring extensive modifications, as for example, in the nature of an attachment which is applicable to conventional scaffolds of various sizes and types.

With the foregoing more important object and features in view and such other objects and features which may become apparent as this specification proceeds, the invention will be understood from the following description taken in conjunction with the accompanying drawings, wherein like characters of reference are used to designate like parts, and wherein:

FIG. 1 is a perspective view of an occupant propelled scaffold in accordance with the invention;

FIG. 2 is an enlarged, fragmentary side elevational view showing one of the traveling wheels with its drive;

FIG. 3 is an end elevational view of the subject shown in FIG. 2; and

FIG. 4 is a fragmentary view, partly in elevation and

2

partly in section, of one of the drive shafts and actuating cranks.

Referring now to the accompanying drawings in detail, the occupant propelled scaffold in accordance with the invention is designated generally by the reference numeral 5 10. As far as the propelling means of the invention are concerned, the structural details of the scaffold are not important and the scaffold may be of any suitable conventional construction which is represented in the drawings by a scaffold frame 11 which supports an elevated platform 12, occupied by a worker. Conveniently, the frame 11 may consist of two pairs of transversely spaced uprights 13, 14 by which the platform 12 is supported, the uprights in each pair being rigidly secured together by transverse rungs 15, thus forming ladders whereby access to the elevated platform may be had.

The scaffold is provided with running gear consisting of a pair of casters 16 at the lower ends of the uprights 13, and a pair of traveling wheels 17 at the lower ends 20 of the uprights 14. Preferably, the wheels 17 may be larger in diameter than the casters 16, although not necessarily so, and if the invention is applied to a conventional, already existing scaffold, the wheels 17 may also be in the nature of casters, as for example, wherein each wheel 25 30 35 40 45 50 55 60 65 70 75 80 85 90 95 100 105 110 115 120 125 130 135 140 145 150 155 160 165 170 175 180 185 190 195 200 9765 9770 9775 9780 9785 9790 9795 9800 9805 9810 9815 9820 9825 9

being disposed within the yoke 18 and secured to one side of the wheel 17, as will be readily apparent. Thus, it will be understood that by rotating the hand crank 25 in one direction or the other, a drive will be imparted to the traveling wheel 17 accordingly. Moreover, since the two cranks 25 are rotatable independently, steering of the scaffold by driving is facilitated.

In terms of assembly from readily available components each of the drive shafts 29 may consist of a suitable length of thin-walled tubing such as is commonly used for electrical conduits. The universal joints 28 and 30 are readily available as such and are usually provided, at least at one end thereof, with a polygonal adapter 28a (or 30a), and the joints 28, 30 may be connected to the associated drive shaft 29 by means of couplers 36 which are non-rotatably inserted into end portions of the tubular drive shaft and are provided with sockets 37 of a polygonal form to receive the polygonal adapters 28a and 30a of the universal joints, as will be understood from FIG. 4. The latter shows the drive shaft connection to the actuating crank 25, but the same arrangement may also be used in connecting the drive shaft 29 to the stub shaft 31 at the traveling wheel 17.

It will be apparent from the foregoing that the scaffold propelling means of the invention enables the occupant of the platform to move the scaffold from one location to another by simply actuating the hand cranks 25 and without the conventionally experienced necessity of leaving the platform in order to move the scaffold by hand from the ground or floor, thus saving considerable time and effort and also avoiding the conventional necessity of employing an assistant to move the scaffold while the worker remains in position thereon.

What is claimed as new is:

1. An occupant propelled scaffold with steering by driving means, comprising in combination a scaffold frame including an elevated occupant supporting platform, running gear for said frame including a pair of transversely spaced

and independently rotatable traveling wheels, a pair of occupant actuated independently rotatable cranks provided on said frame adjacent said platform, a pair of drive shafts connected to the respective cranks and extending downwardly therefrom toward said wheels, and gearing operatively connecting said drive shafts to the respective wheels, said frame also including a pair of transversely spaced uprights, together with a pair of bearing yokes provided at the lower ends of the respective uprights, said traveling wheels being rotatably mounted in the respective yokes each of said yokes including a side plate provided with a recess, a substantially vertical bearing tube provided on said side plate with one end thereof disposed adjacent said recess, and a stub shaft rotatably journaled in said bearing tube, said stub shaft having an upper end operatively connected to one of said drive shafts and said gearing comprising a crown gear rotatable with and disposed at one side of the associated traveling wheel in said yoke, and a spur gear secured to the lower end of said stub shaft, said spur gear projecting through said recess in the yoke side plate into engagement with said crown gear.

2. The device as defined in claim 1 together with a universal joint operatively connecting said stub shaft to the lower end of the associated drive shaft.
